METHOD FOR THE PYROLYSIS OF DIACYL CYANIDES

Alan E. Ardis, Cuyahoga Falls, Ohio, assignor to
 The B. F. Goodrich Company, New York, N. Y.,
 a corporation of New York

No Drawing. Application May 7, 1952,
 Serial No. 286,598

7 Claims. (Cl. 260—465.8)

1 This invention relates to a method for pyrolyzing diacyl cyanides whereby vinylidene cyanide (also known as 1,1-dicyano ethylene) or one of its homologs is obtained, and pertains more particularly to the pyrolytic deacyloxylation of diacyl cyanides in the presence of an inert diluent material.

It is disclosed in U. S. Patent 2,476,270 that the diacyl cyanide, 1-acetoxy-1,1-dicyano ethane, can be pyrolyzed at temperatures in the range of 400° C. to 750° C. to give monomeric vinylidene cyanide, an extremely valuable polymerizable material which is especially useful in the preparation of polymers and interpolymers suitable as synthetic fibers, synthetic resins and plastics.

However, unless the process as described in the patent is carried out at reduced pressures, preferably from 2 to 50 mm. of mercury, the yield of the desired vinylidene cyanide is not as high as is desirable and carbonization of the pyrolysis tube occurs to a considerable extent. This dependency on reduced pressure for optimum results is quite dissatisfactory for a number of other reasons. For example, the production and maintenance of such a vacuum involves the installation of expensive equipment and the necessity for close operational control, both of which add materially to the initial cost and continued up-keep of the pyrolysis plant. Also, reduced pressure makes necessary on a large scale the use of a large pyrolysis tube and/or a high temperature and limits severely the amount of pressure drop through the pyrolysis tube. These conditions in turn lead to a pronounced temperature drop across the gas film at the tube interface with attendant over-cracking along the tube walls and reduced stability of the pyrolysis product. Additionally, reduced pressure pyrolysis requires the use of very low temperatures for condensation of the pyrolysis vapors, this factor again adding to the cost of a pyrolysis plant. As a result of these disadvantages, the process specifically described in U. S. Patent 2,476,270 is not as well suited for practical commercial usage as is desired.

Accordingly, it is an object of the present invention to provide a process whereby 1-acetoxy-1,1-dicyano ethane, as well as other diacyl cyanides, may be readily and economically pyrolyzed with high yields of desired product and without operational difficulties, at atmospheric pressure or even at pressures above atmospheric.

It is a second object of this invention to provide a process whereby diacyl cyanides can be

2 pyrolyzed to give improved yields of monomeric vinylidene cyanide or its homologs, regardless of the operating pressure. Other objects will be apparent from the description which follows.

It has now been discovered that the above and other objects may be readily accomplished by carrying out the pyrolysis of diacyl cyanides in the presence of a diluent material which is inert to the diacyl cyanide and the pyrolysis products thereof. When such inert diluent is utilized, the pyrolysis can be carried out at atmospheric pressure to give good conversion of the diacyl cyanide to monomer and high yields of monomeric vinylidene cyanide or its homologs. Moreover, many other advantages over the reduced pressure pyrolysis or an atmospheric pressure pyrolysis utilizing no inert diluent are attained. For example, the use of an inert diluent increases greatly the stability of the crude pyrolysis product (this being very important in the case of monomeric vinylidene cyanide which is quite difficult to stabilize against polymerization), and decreases overcracking at the gas film layer adjacent the tube interface. Moreover, when the inert diluent is a liquid at room temperature and at atmospheric pressure the melting point of the diacyl cyanide fed to the pyrolyzer is lowered as is the dew point of the pyrolysis product vapors, both of which are quite desirable especially from the standpoint of economy and ease of operation.

The pyrolysis of diacyl cyanides according to the process of the present invention proceeds substantially as follows:

40 wherein R is an acyloxy radical, preferably containing from 2 to 6 carbon atoms, and R' is hydrogen or a lower alkyl radical preferably containing from 1 to 4 carbon atoms. When R' is hydrogen there is produced vinylidene cyanide and carboxylic acid whereas when R' is lower alkyl there is obtained, in place of vinylidene cyanide, a homolog thereof of the formula:

The pyrolysis reaction and recovery of the products can be carried out in several different

3
ways. One preferred method, whereby the desired product is obtained in highest yield with greatest efficiency, consists in adding an inert liquid diluent to the diacyl cyanide, vaporizing the resulting mixture, and passing the vapors at atmospheric pressure through a heated pyrolysis tube, preferably of brass or stainless steel, wherein there occurs decomposition of the diacyl cyanide into monomeric vinylidene cyanide or a homolog thereof, a carboxylic acid, and other unidentified products. The pyrolysis product vapors are then directed into a quench system where the vapors are condensed, preferably by direct contact with a large liquid flow of cold pyrolysis product containing the inert liquid diluent as is more fully disclosed in copending application Serial No. 236,496, filed May 7, 1952. After flash distillation to remove any solid which may be present, the liquid condensate can be utilized without further purification in the preparation of homopolymers and interpolymers of the monomer since the carboxylic acid and any other impurities present in the condensed pyrolysis vapors have no appreciable effect on the polymerization reaction; in fact, the inert liquid diluent provides a very convenient polymerization medium.

Alternatively, the monomeric vinylidene cyanide or homolog can be recovered from the crude pyrolysis product in substantially pure form by distillation, by crystallization from a solvent such as toluene, or by treating the pyrolysis product with a conjugated diolefin such as butadiene or cyclopentadiene which reacts with the monomer to form a solid substituted cyclohexene which can be separated from the carboxylic acid and other impurities and pyrolyzed at temperatures in excess of about 400° C. to give monomeric vinylidene cyanide or homolog and the conjugated diolefin. Also if monomeric vinylidene cyanide is being prepared it can be recovered by utilizing its tendency to autopolymerize and causing it to polymerize as formed as by pouring the liquid product into water to speed up the polymerization, after which the solid polymer can be easily separated from the liquid materials by filtration or decantation. The polymerized vinylidene cyanide can then be depolymerized by pyrolysis, preferably at temperatures of 170° C. to 250° C., to give monomeric vinylidene cyanide, a process described more fully in U. S. Patent 2,535,827.

When the inert diluent is a gas at room temperature and atmospheric pressure, it is preferably introduced into the diacyl cyanide vapors before the vapors enter the pyrolysis tube.

The temperature at which the pyrolytic decomposition takes place may be varied widely without seriously affecting the conversion of diacyl cyanide to monomeric vinylidene cyanide. In general, however, temperatures in the range of 400° C. to 750° C. should be utilized, with optimum conversions being obtained when temperatures in the range of 475° C. to 575° C. are employed. As noted above, operation at atmospheric pressure is preferred but reduced pressures may also be utilized with attendant improvements over the process as carried out in the absence of an inert diluent.

The diacyl cyanide feed rate, that is, the number of parts of diacyl cyanide introduced into the pyrolysis tube per unit of time, may also be varied widely without appreciable effect on the conversion. However, it has been found that the quantity of inert diluent utilized does have a substantial effect on conversion. Accordingly,

5 it is desirable that about 8 to 12 moles of inert diluent be utilized per mole of the diacyl cyanide in order that highest yields of monomeric vinylidene cyanide will be obtained.

10 The material which is utilized as a diluent in accordance with the present invention must be a substance which is inert toward both the diacyl cyanide and the monomeric vinylidene cyanide or homolog under the conditions of pyrolysis, that is, it must neither react with nor affect said compounds at any stage of the pyrolysis process. Included among the substances which are inert toward diacyl cyanides and monomeric vinylidene cyanide and its homologs are compounds which are liquids at room temperature and atmospheric pressure and also compounds which are gases under such conditions. For example, one particularly preferred class of compounds which are successfully employed as 15 inert diluents in the pyrolysis of diacyl cyanides is the liquid aromatic hydrocarbons or halogen substituted aromatic hydrocarbons such as benzene, o, m, or p-toluene, o, m, or p-xylene, monochlorobenzene, dichlorobenzene, trichlorobenzene and the like. Inert diluent gases which 20 may be utilized include nitrogen, hydrogen, helium, methane, ethane, propane and other inert gases. It is to be understood, of course, that the inert diluents disclosed above do not represent all of the inert substances which can be utilized, but the materials disclosed are indicative of the types of substances which can be employed.

25 The process of this invention is especially useful for the pyrolysis of diacetyl cyanide (1-acetoxy,1,1-dicyano ethane). However, other diacyl cyanides of the structure

30 wherein R is an acyloxy radical and R' is a lower alkyl radical, such as 1-propionoxy-1,1-dicyano propane, 1-acetoxy-1,1-dicyano butane, 1-propionoxy-1,1-dicyano ethane, 1-butoxy-1,1-dicyano butane, 1-amyloxy-1,1-dicyano ethane, and the like, also may be pyrolyzed by the process of 35 this invention to give monomeric vinylidene cyanide or a homolog thereof, and a carboxylic acid. 1-propionoxy-1,1-dicyano propane, for 40 example, gives methyl vinylidene cyanide,

45 and propionic acid.

50 The following examples are intended to illustrate more fully the pyrolysis of diacyl cyanides in the presence of an inert diluent. They are not, however, intended to limit the invention, for there are, of course, numerous possible variations and modifications. In the examples all parts are by weight.

Example I

55 A series of pyrolysis reactions is carried out by admixing 1-acetoxy-1,1-dicyano ethane with inert liquid diluents and pumping the resulting solution into a heated glass pyrolysis tube packed with glass helices and maintained at atmospheric pressure. The pyrolysis product vapors are condensed and collected in a cooled receiver and the 60 liquid pyrolysis product analyzed for monomeric

vinylidene cyanide content. The pertinent data are recorded in the following table:

Diluent	Moles diluent per mole 1-acetoxy-1,1-dicyano ethane.	Feed rate (parts 1-acetoxy-1,1-dicyano ethane per minute)	Temperature, °C.	Percent conversion of diacyl cyanide to vinylidene cyanide
Benzene	5.0	0.265	450	30.6
Do	9.0	0.171	565	80.1
74% benzene	14.5	0.104	510	85.5
26% xylene	10.3	0.140	520	80.8
74% benzene	10.3	0.205	515	80.8
26% xylene	10.0	0.165	500	82.5
Chlorobenzene	10.0	0.239	500	79.6
Do	10.0	0.320	525	83.5
Do	10.0	0.320	550	79.6

Example II

Monomeric vinylidene cyanide is prepared by passing vapors of 1-acetoxy-1,1-dicyano ethane at atmospheric pressure through a glass pyrolysis tube which is heated to a temperature of 650° C. A mixture of methane, ethane, and propane, serving as an inert diluent, is passed through the pyrolysis tube together with 1-acetoxy-1,1-dicyano ethane vapors. The crude pyrolysis product vapors are condensed in a cooled receiver and the liquid condensate distilled to give a 75.5% yield of substantially pure monomeric vinylidene cyanide.

In addition to being useful individually, the liquid inert diluents and gaseous inert diluents can be utilized in combination in carrying out the pyrolysis of diacyl cyanides in accordance with the present invention. In the following Example III, the use of inert liquid-gas diluent compounds is shown.

Example III

A series of pyrolysis reactions is carried out by admixing 20 parts of 1-acetoxy-1,1-dicyano ethane with 40 parts of dry monochlorobenzene, heating the mixture to a temperature just below the boiling point thereof, bubbling an inert diluent gas into the melt below the surface thereof and allowing the gas vapors to carry the mixture into a heated pyrolysis tube maintained at atmospheric pressure. The pyrolysis product vapors are then condensed and collected in a cooled receiver and the liquid pyrolysis product analyzed for monomeric vinylidene cyanide content. The inert gaseous diluent utilized, the pyrolysis temperature and per cent yield of monomeric vinylidene cyanide are recorded in the following table:

Inert diluent gas	Pyrolysis temperature, °C.	Percent yield of monomeric vinylidene cyanide
Propane	580	64.7
Nitrogen	580	72.3
Mixture of methane, ethane and propane	550	76.6

The above Examples I to III have shown that excellent yields of monomeric vinylidene cyanide are obtained when diacetyl cyanide is pyrolyzed in the presence of an inert diluent at atmospheric pressure. In the absence of such a diluent atmospheric pressure pyrolysis is so unsatisfactory under the conditions of the examples that the yields of monomeric vinylidene cyanide are no higher than about 10 to 20%.

While working at atmospheric pressure is pre-

ferrered on a plant scale, the process of this invention involving the use of an inert diluent also results in improved yields at lower pressures as is shown in the following Example IV.

Example IV

A series of pyrolysis reactions is carried out in the same general manner as Example I with the exception that reduced pressure is maintained by means of a vacuum pump. In each reaction 40 grams of 1-acetoxy-1,1-dicyano ethane is vaporized by heating, with or without a diluent, and is then passed into the pyrolysis apparatus where the vapors are heated to 650° C.

The pressure maintained, the inert diluent used if any, the duration of the pyrolysis reaction, the yield of monomeric vinylidene cyanide in the condensed pyrolysis product and its stability (expressed as the number of minutes required for formation of polymer when the liquid pyrolysis product is allowed to stand at a given temperature) are recorded in the following table:

Pressure, mm.	Inert diluent	Duration of run, min.	Percent yield of vinylidene cyanide	Stability of product
25	None	70	73.6	32 min. at 70° C.
100	do	35	88.0	29 min. at 70° C.
150	do	50	43.0	13 min. at 70° C.
14	Methane gas, 19-25 cc./min.	50	82	36 min. at 100° C.
200	Methane gas, 27-37 cc./min.	95	69.2	68 min. at 100° C.
50	Trichlorobenzene, 40 grams	45	72.7	23 min. at 100° C.
35	do	110	68.7	36 min. at 100° C.
200	Trichlorobenzene, 40 grams+methane, 19-27 cc./min.	90	60.2	93 min. at 100° C.
15	Trichlorobenzene, 40 grams+methane, 32-43 cc./min.	70	70.5	135 min. at 100° C.
200	Trichlorobenzene, 40 grams+methane, 32-43 cc./min.	140	53.3	76 min. at 100° C.

The data show that higher yields are secured at generally comparable reduced pressures and that the product possesses greater stability against polymerization when the pyrolysis is conducted in presence of an inert diluent in accordance with this invention.

Example V

Example I is repeated except that 1-propionoxy-1,1-dicyano propane is substituted for 1-acetoxy-1,1-dicyano ethane. The conversions of 1-propionoxy-1,1-dicyano ethane to methyl vinylidene cyanide compare favorably with those set forth in Example I.

Although specific examples of the invention have been herein described, it is not intended to limit the invention solely thereto, but to include all of the variations and modifications falling within the spirit and scope of the appended claims.

I claim:

1. The method which comprises pyrolyzing a diacyl cyanide of the structure

wherein R is an acyloxy radical and R' is a member of the class consisting of hydrogen and lower alkyl radicals, at a temperature of 400° C. to 750° C., and in the presence of at least 8 moles of an inert volatile organic diluent, said diluent being free of conjugated diene groups and homo-polymerization accelerating groups for the

pyrolysis product thereby to produce a pyrolysis product comprising a compound of the structure

wherein R' has the same meaning as above.

2. The method of claim 1 wherein the diacyl cyanide is 1-acetoxy-1,1-dicyano ethane and the pyrolysis product comprises monomeric vinylidene cyanide.

3. The method of preparing monomeric vinylidene cyanide which comprises pyrolyzing 1-acetoxy-1,1-dicyano ethane at atmospheric pressure at a temperature of 400° C. to 750° C. and in the presence of an inert diluent selected from the class consisting of liquid aromatic hydrocarbons and liquid halogenated aromatic hydrocarbons, there being present at least 8 moles of said compound per mole of the said 1-acetoxy-1,1-dicyano ethane.

4. The method of claim 3 wherein the inert diluent is benzene.

5. The method of claim 3 wherein the inert diluent is chlorobenzene.

6. The method of claim 3 wherein the inert diluent is a mixture of benzene and xylene.

7. The method of preparing monomeric vinylidene cyanide which comprises pyrolyzing 1-acetoxy-1,1-dicyano ethane at atmospheric pressure, at a temperature of 400° C. to 750° C. and in the presence of a gaseous saturated aliphatic hydrocarbon.
